TIMER WITH FLOATING INDICATOR

Walter G. Von Meyer, 1504 Port Jefferson Road,
Sidney, Ohio 45365

Filed Aug. 5, 1966, Ser. No. 3,365

Term of patent 14 years

(Cl. D42—7)

FIG. 1 is a front elevational view of a timer with floating indicator showing my new design,

FIG. 2 is a side elevational view thereof,

FIG. 3 is a top plan view thereof, the bottom plan view being a mirror image thereof; and

FIG. 4 is a cross-sectional view thereof taken on line 4—4 of FIG. 1.

The dominant features of my design reside in those portions shown in full lines.

I claim:

The ornamental design for a timer with floating indicator, substantially as shown and described.
